FREEZER CYLINDER CENTERING MEANS

James W. Townsend, Winchendon, Mass., assignor of one-half to The Alaska Freezer Co., Inc., Winchendon, Mass., a corporation of Massachusetts, and one-half to Sears, Roebuck and Co., Chicago, Ill., a corporation of New York

Application December 16, 1939, Serial No. 309,631

1 Claim. (Cl. 259—1)

This invention relates to an ice-cream freezer commonly made in domestic sizes and manually operated.

It is the general object of my invention to provide an improved and simplified construction in a domestic ice-cream freezer, by which more economical manufacture is made possible.

A further object of my invention is to provide an improved means for centering the rotating cylinder in the freezing tub.

My invention further relates to arrangements and combinations of parts which will be herein-after described and more particularly pointed out in the appended claim.

A preferred form of the invention is shown in the drawings, in which

Fig. 1 is a partial side elevation of my improved freezer, with the cover raised and certain parts shown in section;

Fig. 2 is an enlarged partial sectional side elevation showing the cover-locking devices;

Fig. 3 is a partial plan view looking in the direction of the arrow 3 in Fig. 1;

Fig. 4 is a sectional side elevation, taken along the line 4—4 in Fig. 3;

Fig. 5 is a partial bottom view, looking in the direction of the arrow 5 in Fig. 4;

Fig. 6 is a partial plan view with the cover omitted;

Fig. 7 is a side elevation, taken in the direction of the arrow 7 in Fig. 6;

Fig. 8 is a partial sectional plan view, taken along the line 8—8 in Fig. 1;

Fig. 9 is an enlarged detail side elevation, looking in the direction of the arrow 9 in Fig. 1; and

Fig. 10 is a detail sectional view, taken along the line 10—10 in Fig. 4.

Referring to Fig. 1, my improved freezer comprises a tub or container 10, a cover 11, a cylinder or can 12, a dasher 13, a main shaft 14 and a crank handle 15. The cover 11 is preferably made of wood of substantial thickness and is machined, as best shown in Fig. 4, to provide a central gear opening 20 having a semi-circular recess 21 at one side and having a second and circular recess 22 aligned with the recess 21 but nearer the periphery of the cover. A radial opening 23 is also provided which loosely receives the main shaft 14.

The shaft 14 is rotatably mounted in bearings 24 and 25 (Figs. 4 and 7) which project upward from a gear frame member 30 which is secured to the inside of the cover 11 in any convenient manner as by screws 31 (Fig. 5). The cover

had a downwardly projecting portion which is recessed at 32 (Fig. 10) to receive the frame member 30 and to prevent relative angular movement thereof. The recess 32 extends across the grain of the wood cover 11, so that the frame member 30 acts also to stiffen the cover to prevent warping thereof. When the member 30 is secured in position, the bearings 24 and 25 are received in the recesses 21 and 22 previously described.

After the member 30 is secured in position, the shaft 14 may be inserted through the radial passage 23 and the bearings 24 and 25, as shown in Fig. 4, and a bevel gear 33 is then screwed fast on the inner end of the shaft 14. The bevel gear 33 meshes with an upper bevel gear 35 and also with a lower bevel gear 36.

The upper gear is provided with a hub 37 (Fig. 4) projecting downward into a bearing 38 in the frame member 30. A cap 40 is centered in the opening 20 in the cover 11 and is secured in position by screws 41 (Fig. 3). The cap 40 not only closes the opening 20 in the cover 11 but also provides a surface 42 (Fig. 4) to take the upward thrust of a ball 43, axially mounted in the upper surface of the gear 35. Upward displacement of the gear 35 relative to the gear 33 is thus prevented. The hub 37 is provided with the usual square axial opening 45 (Fig. 5) to receive the squared upper end of the dasher shaft 46 (Fig. 1).

The lower bevel gear 36 is formed on the cover 48 of the can 12 and acts through the cover to rotate the can in one direction while the gearing described rotates the dasher in the opposite direction, all as is customary in ice-cream freezers.

The frame member 30 is cut away as indicated at 50 (Fig. 6) to provide clearance for the bevel gear 33 and is laterally enlarged and upwardly arched as indicated at 51 (Fig. 4) to provide clearance for the gear 36.

For the purpose of securing the cover 11 to the tub 10, I provide offset lugs 52 (Figs. 1 and 2) on the under side of the frame member 30, which lugs are adapted to engage flanges 60 on segmental cam plates 61, mounted within the freezer at opposite sides thereof and preferably secured in position by the bolts 62 by which the usual bail 63 is also secured. Each flange 60 is provided with an inclined lower surface 65 and with a shoulder 66.

In assembling the parts, the cover is placed in position with the lugs 52 clearing the flanges 55 60 at their left-hand ends, as shown in dotted

lines in Figs. 6 and 9. The cover is then turned clockwise, as indicated by the arrow *a*, to the position shown in Fig. 6 or to such other angular position as causes the lugs 52 to firmly engage the inclined cam surfaces 65 of the flanges 60. The cover 11 is thus secured firmly in position, with the gearing in the cover positioned in operative relation to the squared shaft 46 and to the gear 36 within the freezer.

The plates 61 are provided with additional flanges 70 having inclined upper portions 71 and offset horizontal portions 72. These flanges 70 position and support the spaced end members 80 of a centering ring 82. The ring 82 and associated end members 80 may conveniently be formed by bending two narrow flat steel strips to the shape shown in Fig. 8 and securing them together by spot-welding at the points 83.

The end members 80 are somewhat resilient and are normally closer together than the flanges 70. Consequently, when the centering ring is placed in position, the end members 80 are spread part and firmly grip the flanges 70, while at the same time they are supported by the offset flange portions 72. The inclined portions 71 facilitate assembly of the centering ring in the freezer. The ring 82 fits the outside of the can 12 loosely but holds the parts substantially in the axial position shown in Fig. 1 until the cover and driving mechanism is assembled therewith.

It will be seen that I have provided an improved freezer construction in which the driving mechanism is supported on and reinforces the wood cover and is securely positioned relative thereto, and in which a simple and improved device centers the can and dasher within the tub during the packing thereof and during the attachment of the cover thereto.

I have also provided very simple means for locking the cover in position and for securely closing and sealing the upper end of the freezer, thus excluding dirt therefrom and also much improving the heat-insulation for the frozen mixture.

Having thus described my invention and the advantages thereof, I do not wish to be limited to the details herein disclosed, otherwise than as set forth in the claim, but what I claim is:

In a freezer having a tub and a rotating can, that improvement which consists in providing a centering ring for said can having spaced resilient end portions, and in providing plates secured to opposite inside portions of said tub and having supporting flanges for said end portions, said flanges having converging inclined upper portions, vertical middle portions, and outwardly offset horizontal lower end portions.

JAMES W. TOWNSEND.
